[57] **CLAIM**

The ornamental design for a lottery ticket display case, as shown and described.

DESCRIPTION

FIG. 1 is a front perspective view of a lottery ticket display case showing my new design;

FIG. 2 is a front elevational view thereof;

FIG. 3 is a rear elevational view thereof, with environmental structure shown in broken lines for purposes of illustration only and forming no part of the claimed design;

FIG. 4 is a right side elevational view thereof;

FIG. 5 is a left side elevational view thereof;

FIG. 6 is a top plan view thereof; and,

FIG. 7 is a bottom plan view thereof.

The dotted lines in FIG. 1 represent the shape and positioning of a computer terminal and form no part of the claimed design.
